Ses. 62

Samuel H. Vose, Albany, N.Y.

Letters Patent (Design No. 62) dated 25 July 1840
ante dated March 21st 1840

The Schedule referred to in these Letters Patent and making
part of the same.

To all whom it may concern:

Be it known that I, Samuel H. Vose of Albany in the County of Albany
State of New York, have invented or produced a new ornamental design for
a Box Stove, and I do hereby declare that the following is a full, ^{clear} and
exact description of the same, reference being had to the accompanying draw-
ings, making part of this specification. —

Fig. 1 represents a stove after my design. Fig. 2 shows a side (both
sides being alike) with the detail of ornament upon a larger scale. But
one half is here represented (as is likewise the case in Fig. 3) in order to save

labour in drawing, with the other values being similar to, and symmetrical with, that given. A vase of flowers $\alpha\alpha$ occupies a panel at each end. — bb is also a vase of different form containing flowers. This latter vase appears also upon the ends Fig. 3 which are both alike. The whole of the decorations are in the style of Louis XIV, and although not easily described in words, are fully represented in the drawings. The borders indicated at c.c. Figs. 2 & 8 are continued entirely around the inner panels. The border dd is also continued around the inner panels.

(What I claim as my invention and desire to secure by letters Patent is, the combination and arrangement of ornamental figures herein shown and described, forming an ornamental Design for a Bay Stove.

Witnesses,

John S. Ellison
